(57) **CLAIM**

The ornamental design for a filter media, as shown and described.

DESCRIPTION

FIG. 1 is a perspective view of a filter media showing my new design;

FIG. 2 is a front view of a filter media showing my new design;

FIG. 3 is a perspective view of a filter media in a second embodiment of my new design; and,

FIG. 4 is a front view of a filter media in a second embodiment of my new design.

The broken lines shown in the figure is for illustrative purposes only and form no part of the claimed invention.
